UNITED STATES PATENT OFFICE.

JOHN A. BECHTEL, OF TARENTUM, PENNSYLVANIA.

GLASS-STOWING TOOL.

1,306,993.

Specification of Letters Patent. Patented June 17, 1919.

Application filed June 21, 1918. Serial No. 241,278.

To all whom it may concern:

Be it known that I, JOHN A. BECHTEL, a citizen of the United States, residing at Tarentum, in the county of Allegheny and State of Pennsylvania, have invented a new and useful Improvement in Glass-Stowing Tools, of which the following is a full, clear, and exact description, reference being had to the accompanying drawings, forming part of this specification, in which—

Figure 1 is a sectional diagrammatic plan view illustrating the use of my invention.

Fig. 2 is a plan view, partly broken away, of the blade of the tool.

Fig. 3 is a side view of the same.

Figs. 4 and 5 are sectional views taken on the lines IV—IV and V—V, respectively, of Fig. 2, and

Fig. 6 is a plan view of a portion of one of the tool handles.

My invention has relation to tools of the class which are employed for pushing sheets or plates of glass through leer annealing ovens and commonly known as glass stowing tools.

The object of my invention is to provide a tool of this character having its blade or portion which comes in contact with the glass of greater length than the linear diameter of that edge of the glass plate or sheet with which the tool contacts, whereby certain important advantages hereinafter stated are obtained.

A further object of my invention is to provide a tool of this character which can be readily reversed in operation so as to prevent warping.

My invention also provides a stowing tool which results in less injury to the glass and which is simple in its construction and mode of operation.

The nature of my invention will be best understood by reference to the accompanying drawing in which I have shown a preferred embodiment thereof, and which will now be described, it being premised, however, that various changes can be made in the details of construction and arrangement of the parts of the tool, without departing from the spirit and scope of my invention, as defined in the appended claims.

In the preferred form of my invention, I construct the blade of the tool of a central longitudinally extending I-beam 2, to the opposite flanges of which are rigidly secured the channels 3 having their flat surfaces

outermost. The length of the I-beams and of the channels is greater than the width of the largest plate or sheet with which the tool is to be used where front stows are made; 60 and longer than the length of the longest plate or sheet where the tool is used for side stowing.

The tool is provided with one or more handles 4, which are detachably engaged 65 with the blade portion. The connection between the handles and the blades may be conveniently made by providing the pins or studs 5 which project inwardly into the interior of the blade and each of which is designed to be engaged by an opening 6 in the end of the handle 4. This end portion of the handle is provided with a heel 7 adapted to engage the edge of the I-beam flange in the manner shown in Fig. 4, and thus prevent 75 strains on the channel irons.

I preferably provide four sets of these pins arranged as shown in Fig. 4, which permits the handles to be readily engaged with the blade portion when the latter is reversed 80 either end for end or turned upon either of its channel iron surfaces. The end portions of the handles are bent upwardly near where they engage with the pinions or studs 5, so as to extend outwardly through the 85 openings between the side flanges of the channel irons and out of contact with the oven bottoms.

The manner of using the tool will be clearly apparent from Fig. 1 in which both 90 side and end stowing are illustrated. The tool is placed against the edge of the sheet and is pushed by means of the handles to move the sheet or plate 3 in the oven.

The advantages of my invention will be 95 apparent to those familiar with the use of tools of this class. The stowing tools commonly in use at the present time have blades with a single working surface which is shorter than the plates being stowed. The continued use of these tools on the oven bottoms causes grooves to be worn in such bottoms; and as the glass sheets or plates are plastic when pushed through the ovens, they take the form of the oven bottoms, and when such bottoms are grooved, the plates have irregular top and bottom surfaces. This means that a longer time is required for the subsequent grinding operations and frequently bad spots are left in the plate which necessitates cutting the finished product, and reduces the plate to smaller sizes. By the 100 105 110

use of my improved tool, which has a continuous bearing on the oven bottom for a length greater than the length or width of the sheet, this grooving of the oven bottom is entirely obviated and they are kept smooth and level.

With the tools now in use it also frequently occurs that the sand used in the ovens to prevent plates sticking to the bottoms collects in bunches or piles which cause bulges in the plates, resulting in irregular surfaces. In the use of the longer tools, in accordance with my invention, the sand is evenly distributed over the oven bottoms as the tool is moved back into the original position after each plate has been pushed into the next oven.

A still further advantage resulting from my improved tool is due to the increased bearing surfaces against the plates or sheets, thereby preventing what is commonly known as "push-ups", or dented edges of the plates.

With the tools now generally in use the leers must be stopped at intervals, and the fires put out in order that the oven bottoms may be redressed to remove stowing tool grooves. This is obviated by my invention.

By reason of the reversibility of the tool both end for end and also to bring either side into contact with the oven bottom, warping and misshaping of the channel irons from the heat of the ovens is prevented.

I claim:

35 1. The combination with a glass leer chamber, of a glass-stowing tool movable therein having a blade of substantially the full width of the chamber with allowance for slight end movement of the blade, and 40 a handle projecting through the chamber wall for moving the tool, whereby grooving of the floor within the lateral dimensions of the glass plates or sheets is avoided, substantially as described.

45 2. A glass-stowing tool having a blade provided with upper and lower surfaces, each adapted for contact with the oven bottom, and means whereby a handle may be connected to said blade in either one of two reversed positions, substantially as described.

50 3. A glass-stowing tool having its blade provided with upper and lower surfaces, each adapted to contact with the oven bottom, and means whereby a handle may be

connected to said blade in either position of the latter when turned edge for edge and also in either position thereof when turned end for end, substantially as described.

4. A glass-stowing tool comprising a blade which is reversible edge for edge and also end for end, a detachable handle, and means for attaching said handle to the blade in all of the reversed positions of the latter, substantially as described.

5. A glass-stowing tool having a blade portion of greater length than the liner dimension of that edge of the plate or sheet with which the tool contacts in use, and a handle member adapted for detachable engagement with the blade portion, the blade portion being provided with a plurality of devices whereby a handle may be engaged therewith in reversed positions of the blade portion.

6. A glass-stowing tool having its blade portion comprising a central I-beam member, and channel irons secured to the flanges of the I-beam; substantially as described.

7. A glass-stowing tool having its blade portion comprising a central I-beam member, and channel irons secured to the flanges of the I-beam, together with a handle having means for its engagement and disengagement from the blade portion through the openings between the flanges of said channel irons; substantially as described.

8. A glass-stowing tool comprising a central beam member and channels secured to opposite edges of the beam member, and a detachable handle; substantially as described.

9. A glass-stowing tool, comprising a blade reversible end for end and also edge for edge and having four different handle-attaching means, each designed for use in a different position of the blade, substantially as described.

10. The combination with a leer chamber, of a glass-stowing tool therein having a blade of substantially the full width of the chamber with allowance for slight end movement of the blade, and a detachable handle projecting from the said tool through the wall of the chamber, said tool being arranged to receive the handle in different parts of the tool, substantially as described.

In testimony whereof, I have hereunto set my hand.

JOHN A. BECHTEL.
